UNITED STATES PATENT OFFICE.

GEORGE F. WADDELL AND WILLIAM J. EVANS, OF ANACONDA, MONTANA.

CHILIAN MILL.

SPECIFICATION forming part of Letters Patent No. 709,689, dated September 23, 1902.

Application filed January 11, 1902. Serial No. 89,365. (No model.)

To all whom it may concern:

Be it known that we, GEORGE F. WADDELL and WILLIAM J. EVANS, citizens of the United States, residing at Anaconda, Deerlodge county, Montana, (post-office address Anaconda, Montana,) have invented certain new and useful Improvements in Chilian Mills, of which the following is a specification.

This invention pertaining to improvements in the construction of Chilian mills will be readily understood from the following description, taken in connection with the accompanying drawings, in which—

Figure 1 is a vertical section of a mill embodying our invention, the section being taken on line *a* of Fig. 2; Fig. 2, a plan of the mill; Fig. 3, a side elevation of the spider and driver, part appearing in section in the plane of line *b* of Fig. 2; and Fig. 4, a plan 20 of the spider, the shaft appearing in section in the plane of line *c* of Fig. 3.

In the drawings, 1 indicates the base; 2, the pan; 3, the die; 4, the screens; 5, the curb; 6, the shaft-bearing in the pan-bottom; 7, the main shaft; 8, the driving-shaft; 9, gearing connecting the driving-shaft to the main shaft, all the parts thus far referred to being of ordinary construction; 10, a sphere mounted upon the shaft and capable of vertical movement thereon and splined thereto or not, as may be desired; 11, the spider-hub, provided with a spherical center engaging the sphere; 12, cap secured to the hub and forming the upper portion of the spherical bearing therein; 13, journal-arms projecting rigidly from the spider, the spider being shown as arranged for three rolls; 14, rolls with their hubs bearing upon the journal-arms, the latter being provided with keeper-nuts to prevent the outward displacement of the rolls; 15, drag-arms projecting outwardly from the spider-hub between the journal-arms, these drag-arms being horizontally slotted at their outer extremities in the illustration; 16, journal-pins vertically disposed across the slots in the drag-arms; 17, the driving-disk, the same being splined to the main shaft above the spider and shown as having the usual annular water-pan form and the usual dis-

charge-spouts; 18, drag-bosses projecting 50 downwardly from the driving-disk, their lower ends being substantially in the plane of the slots in the drag-arms of the spider; 19, journal-pins firmly keyed into these bosses and projecting downward therefrom; 20, 55 links, one for each drag-arm, connecting the journal-pins of the drag-arms with those of the drag-bosses, these links being so thin as to have vertical play in the slots of the drag-arms and also upon the journal-pins of the 60 drag-bosses; 21, the usual scrapers or distributors carried by the driving-disk; 22, an adjusting-nut threaded on the upper portion of the main shaft and coupled to the driving-disk and serving to vertically adjust 65 the latter, and 23 a lock-nut for the adjusting-nut.

The main shaft transmits the driving power to the driving-disk, and this disk drives the spider through the medium of the drag-bosses, 70 &c. The spider with its rolls may rise and fall independently of the driving-disk, and it may also rock upon the sphere, the flexible character of the link connections permitting these free motions of the spider and rolls. 75 The rigid journal-arms 13 upon the spider give it great radial dimension and produces a peculiarly rigid and satisfactory roll-carrying structure.

We claim as our invention—

1. The combination, substantially as set forth, of a main shaft, a sphere mounted thereon, a spider-hub loosely mounted on the sphere, journal-arms projecting rigidly from the hub, rolls mounted on the journal-arms, a 85 die coöperating with the rolls, drag-arms projecting from the hub, journal-pins carried by the drag-arms, a rotary annular pan discharging on the die and rolls, secured to the shaft above the hub, journal-pins projecting from 90 the bottom of the rotary pan, and links connecting the journal-pins of the water-pan with those of the drag-arms.

2. The combination, substantially as set forth, of a main shaft, a sphere mounted thereon, a spider-hub mounted on the sphere, journal-arms projecting from the hub, rolls mounted on the journal-arms, a die coöperating with

the rolls, drag-arms projecting from the hub, journal-pins carried by the drag-arms, a driving-disk secured to the shaft above the hub, journal-pins projecting from the driving-disk 5 to positions in front of the drag-arms, and links connecting the journal-pins of the driving-disk with those of the drag-arms, said links having vertical play upon said journal-pins.

GEORGE F. WADDELL.
WILLIAM J. EVANS.
